UNITED STATES PATENT OFFICE

JOHN M. ALLEN, OF TORONTO, ONTARIO, CANADA, ASSIGNOR TO SCOTT & WILLIAMS,
INCORPORATED, OF NEW YORK, N. Y.

SEAMLESS HOSIERY

Application filed August 12, 1927, Serial No. 212,527. Renewed June 11, 1928.

The principal objects of this invention are to produce a stocking in which the foot is formed to provide a very neat and snug fitting garment which will be free from seams 5 and loose irregular portions which are very uncomfortable to wear, thereby providing a stocking very neat in appearance and of a highly desirable quality.

A further and very important object is to 10 effect a saving of time and material in the manufacture of hosiery.

The principal feature of the invention consists in the novel construction of the toe 15 of the stocking which is knitted in two halves and looped together, a gusset being formed between the meeting edges to effect the widening of the toe.

In the drawings, Figure 1 is an elevational view of my improved hose as knitted, on the 20 foot.

Figure 2 is a side view of the knitted foot shown flat.

Figure 3 is a side view illustrating the manner in which the fabric of the toe portion is 25 knitted prior to the looping of the two halves of the toe.

Figure 4 is a detail showing a modification of the gusset.

In the manufacture of this stocking which 30 is made on a seamless knitting machine, the heel portion A is formed in the usual manner, as is the major portion B of the foot which is extended to the point C, at which point the machine is operated to knit the top 35 and bottom toe sections separately. Each course of stitches in both the top and bottom sections is reduced in length by removing one or more needles from action. In this manner a tapering toe is produced which tapers 40 in both directions from the point C.

The removing of needles from action continues until the minimum number of stitches desired across the toe end is reached then on either the top or bottom section of the toe 45 structure the knitting is continued to form a gusset D. This gusset is formed by first returning the major number of needles in either the upper or lower half into action to knit a course of stitches along the tapered edge of 50 such upper or lower part of the toe. A lesser

number of stitches is knitted in this course than the number of stitches around the edge of the toe section as illustrated in Figures 1 and 2. A certain definite number of needles are brought into action to knit the edge course 85 and the next succeeding course is increased in length by returning one or more needles into action and so on so that each succeeding course in the gusset is increased in length by the introduction of one or more needles, thus 60 producing a tapering effect at the end of the gusset. The gusset is preferably from six to eight courses in depth and it is shorter in length than the edge of the tapered toe section to which it is knitted. The gusset may, 65 if desired, be formed by decreasing the length of the successive courses of stitches, as illustrated in Figure 4.

Upon the completion of the gusset, the entire complement of needles of the machine is 70 thrown into operation and a plurality of courses are knitted to the edge of the gusset and to the edges of the tapered toe sections to form a plurality of looping courses E illustrated in Figure 3. The desired looping 75 course is then put on a looping machine and the edges of the upper and lower separately knitted toe structures are connected together by the loop stitching F which extends completely around the toe end.

In making the toe pouch by knitting both 80 portions of the toe simultaneously, a considerable saving of time in the operation of the knitting machine is effected, consequently the manufacturer will be able to produce a 85 very considerably increased number of stockings in the working time.

In manufacturing the toe of a silk or fine 90 thread stocking in the manner described, the instep yarn may be continued any desired distance into the narrowing top toe section and it may then be changed to a cotton yarn or reinforcing yarn while the whole bottom section of the foot may be knitted with cotton if 95 desired. The continuation of the instep yarn, which is knitted tightly, into the toe section materially shortens the length of the top of the foot and an excellently fitting stocking is produced. The insertion of the 100 gusset D around the narrow end of the toe en-

ables the commencement of the narrowing of the toe sections to be extended much farther back toward the ball of the foot than is usual as the gusset widens out the narrow point and tapers off and discontinues short of the full length of the tapered toe sections and eliminates bulging surplus material and "dog ears" at the ends of the tapered toe sections.

This stocking can be very advantageously manufactured on the type of knitting machine known as a "Split Foot" machine which utilizes a double feed for the whole foot structure.

What I claim as my invention is:

15. 1. A stocking having a toe formed with the top and bottom halves each knitted integrally with the foot and a gusset knitted between said halves and extending around the toe end, the edges of one of said halves and the gusset being stitched together.

20. 2. A stocking formed with light weight yarn in the instep and a heavier yarn in the toe, said toe being formed with the tapering top and bottom halves knitted integrally with the foot and having the light instep continued for a number of courses into the top half of the toe, the remainder of the top half being of a heavier yarn, the edges of the top and bottom halves being stitched together.

25. 3. A stocking formed with a light weight yarn in the instep and a heavier yarn in the toe, said toe being formed with the tapering top and bottom halves knitted integrally with the foot and having the light instep continued for a number of courses into the top half of the toe, the remainder of said top half being reinforced, a gusset being knitted between said halves and extending around the toe end and the edges of one of said halves and gusset being looped together.

30. 4. A stocking having tapering upper and lower toe sections knitted separately in continuation from the foot, a gusset of several courses and of lesser length than the edges of the toe sections being knitted with the courses extending around the end of one of the tapering toe sections, the edges of the gusset and adjacent toe section being joined completely around the end of the toe.

35. 5. A seamless foot hose having a full circle of stitches in the foot portion, the upper toe portion forming a continuation thereof and being knitted with a decreasing number of stitches in each succeeding course to the toe end and the bottom toe portion being similarly formed, one of said toe portions having a plurality of extra courses of stitches extending around the end for the major portion of the length of the edge thereof and being 40 knitted thereto to form a gusset with tapered ends, and a course of loop stitches connecting the free edge of the inserted gusset and the adjacent toe section to the edge of the other toe section.

45. 6. In a stocking formed with a light yarn

in the instep and a heavier yarn in the toe, the foot section having the toe end knitted in two separate tapering halves each formed integral with the foot, the inner ends of the tapering portions commencing at the ball portion of the foot of the wearer, the instep yarn continuing into the top half and said top half being finished with a heavier yarn, one of said sections having a plurality of inserted courses knitted to the tapering edges thereof, the ends of said inserted courses being tapered off and meeting the tapered knitted edge of the toe section, and a row of loop stitching extending along and joining the tapered edges of the two toe sections and the tapered edge of one of the toe sections with the tapered ends of the inserted courses and the stitches of the outer course of the inserted courses to complete the toe of the stocking.

50. 7. A method of knitting a stocking, comprising knitting the foot, then knitting the upper and lower toe sections separately and in continuation of the foot progressively removing needles from action at the ends of the courses to form tapering sides, then immediately returning a plurality of needles into action to knit a course around the end of one of the toe sections of a lesser length than the edge thereof, then knitting a plurality of courses of progressively differing lengths to the first insert course producing a gusset tapering to the ends, then stitching the end and tapered edges of the other toe section to said gusset and the tapered edges of the tapered section extending beyond the tapered edges of the gusset.

55. 8. A method of making hosiery, comprising knitting the foot with a light yarn instep and a reinforced sole, then removing needles out of action to knit a tapered reinforced toe bottom and to knit a tapering toe top continuing the instep yarn beyond the commencement of the taper for a multiplicity of courses, then effecting a yarn change from a light instep yarn to a reinforcing yarn in the toe top and finishing the toe top with a reinforcing yarn tapering it to a narrow end, then knitting a gusset to the edge of the tapered toe top of a plurality of courses extending back to the juncture of the instep yarn with the reinforced yarn, then looping the edge of the reinforced bottom toe section to the edge of the gusset and to the ends of the courses of the instep yarn extending into the toe section past the commencement of the taper.

60. 9. A method of making a stocking, comprising knitting the foot to a point coincident with the greatest width of the foot of the wearer, the yarn of the sole being reinforced and heavier than the instep yarn, then removing needles from action and continuing the knitting of the instep yarn into a tapered toe section and knitting the sole yarn into a tapered toe section, making a yarn change

in the top portion intermediate of its length completing the top with the reinforced yarn, then knitting to the end and tapering edges of one of the toe portions a plurality of courses to form a gusset with tapering ends, the ends of the gusset to correspond with the length of the tapered edge of the reinforced upper toe section, the knitting looping courses around the edges of said toe sections, and finally looping the edges of the toe sections together joining the reinforced bottom toe sections to the light instep yarn of the upper toe section and the edge of the gusset with the remaining edge of the toe section.

15 10. A method of making a stocking, comprising knitting the foot to a point coincident with the greatest width of the foot of the wearer, using a light yarn in the instep and a reinforced yarn in the sole, then progressively removing needles from action and continuing the knitting of the reinforced sole yarn into a tapered toe bottom and of the light instep yarn into a tapered toe top, making a yarn change intermediate of the length 25 of the toe top, then joining the edges of the top and bottom toe sections.

11. A seamless stocking having a foot section and upper and lower tapered toe segments each knit separately and integrally with the foot section, in combination with a gusset knit to the edge of one of said sections, the edge of the other section being stitched to the edge of the gusset and the edges of the toe sections extending beyond the gusset.

35 12. A seamless stocking having a foot section and upper and lower tapered toe segments each knit separately and integrally with the foot section, in combination with a gusset knit to the edge of one of said sections, the edge of the other section being stitched to the edge of the gusset and the edges of the toe sections extending beyond the gusset, the tapering of the toe segments extending from the widest point of the foot 45 of the wearer to a narrow end at the point of the toe.

JOHN M. ALLEN.
